(57) CLAIM

The ornamental design for a portable air cleaner, as shown and described.

DESCRIPTION

FIG. 1 is a perspective view of the portable air cleaner showing my new design;

FIG. 2 is an enlarged top plan view of the portable air cleaner of FIG. 1;

FIG. 3 is an enlarged bottom plan view of the portable air cleaner of FIG. 1;

FIG. 4 is an enlarged left side elevational view of the portable air cleaner of FIG. 1.

FIG. 5 is an enlarged front elevational view of the portable air cleaner of FIG. 1.

FIG. 6 is an enlarged right side elevational view of the portable air cleaner of FIG. 1; and,

FIG. 7 is an enlarged rear elevational view of the portable air cleaner of FIG. 1.

The broken line showing of environmental structure in FIG. 1 is for illustrative purposes only and forms no part of the claimed design.
